UNITED STATES PATENT OFFICE.

GEORGE W. BUFFORD, OF BUFFALO, NEW YORK, ASSIGNOR TO J. H. WILLIAMS & COMPANY, OF BROOKLYN, NEW YORK, A CORPORATION OF NEW YORK.

CHAIN PIPE-WRENCH.

1,327,309.

Specification of Letters Patent.

Patented Jan. 6, 1920.

Application filed March 14, 1918. Serial No. 222,329.

To all whom it may concern:

Be it known that I, GEORGE W. BUFFORD, a citizen of the United States of America, residing in Buffalo, Erie county, State 5 of New York, have invented certain new and useful Improvements in Chain Pipe-Wrenches, of which the following is a specification.

This invention relates to improvements in 10 chain pipe wrenches and aims to provide improvements therein.

The invention provides a chain pipe wrench with a flat link chain, which is more convenient in use, or "handier" and efficient 15 than chain pipe wrenches with flat link chains heretofore in use.

An embodiment of the invention is illustrated in the accompanying drawings, wherein—

20 Figure 1 illustrates, in side elevation, a wrench embodying the present invention; Fig. 2 is a cross-section, on the line II—II,

Fig. 1;

Fig. 3 is a detail view, partly in section, 25 of the connection between the chain and wrench.

In said drawings, letter A designates the stock, B, the jaw and C, the chain. The chain is a flat link chain composed of disks of 30 steel c connected by pintles c' , and hence its flexibility is mainly in a plane at right angles to the axes of the pintles. The jaw B may be of any type; that here shown being of the character disclosed and claimed in the 35 application of Amborn and Bufford, Serial No. 64,266, filed November 30, 1915.

D designates the connection between the chain and the stock. The chain is connected to one end of the connection, as by means 40 of the pin d . The connection comprises means, such as an eye d' , which is fastened to the stock in a manner to permit the connection D and chain C to swing around a pipe in a plane with the stock, as for example, by a pin d^2 passing through lugs a upon the stock A.

Within the connection D there is provided a swivel, this being conveniently formed by making the connection in two parts, d^3 and 50 d^4 , one with a socket d^5 and the other with a shank d^6 fitting within the socket and having its end flattened to bear upon a shoulder d^7 within the socket.

The pivotal connection of the connection

D around the pin d^2 permits the chain to 55 fit around the pipe in the usual way, *i. e.*, in a plane passing through the stock, and the swivel admits of convenient manipulation in applying the chain to the pipe.

In pipe work, especially overhead work, 60 it is usually most convenient and speedy for the workman to throw the chain over a pipe to one side of the jaw, and let the chain by its weight fall into approximate working position around the pipe, rather than 65 to pass and "feed" the chain over and around the pipe in line with the jaw. Such an application of the chain is readily effected with a welded link chain, and in the case of a flat link chain, may be effected by 70 utilizing the means provided by the present invention.

The combination of the pivotal and swivel connections permits of the strain on the 75 swivel being taken axially of the swivel, and permits of easier turning of the parts of the swivel in the application of the chain around a pipe and in the use of the wrench.

The wrench, set forth herein, is broadly 80 claimed in the application of Amborn and Bufford, Sr. No. 64,266, filed November 30, 1917.

What is claimed is:—

1. A wrench having a body portion comprising a jaw and a chain adapted to clamp 85 the work against said jaw, said chain being composed of a series of pivoted links, the chain being flexible in one plane and substantially inflexible in a plane transverse of the pivotal axis of the links, having a 90 swinging connection with the body of the wrench, and having a swivel connection between the swinging connection and the free end of the chain and being adjacent to said swinging connection. 95

2. A chain pipe wrench comprising a stock, a jaw, a chain, composed of a series of pivoted links, the chain being flexible in one plane and substantially inflexible in a plane transverse of the pivotal axis of the 100 links, and a connection between the chain and stock, said connection having a pivotal connection with the stock and having a swivel therein.

In witness whereof, I have hereunto 105 signed my name.

GEORGE W. BUFFORD.
